BREAST FORM

Herbert A. Austin, Boston, Mass., assignor to The
H. A. Austin Company, Incorporated, Worcester,
Mass., a corporation of Massachusetts

Application February 7, 1939, Serial No. 255,089

1 Claim. (Cl. 2—267)

The principal objects of this invention are to provide a breast form of a character in which, when it has been collapsed, it will automatically restore itself to normal convex position, and to provide a construction which prevents injurious pressure on the natural breast.

Other objects and advantages of the invention will appear hereinafter.

Reference is to be had to the accompanying drawing, in which

Fig. 1 is a front view of a preferred embodiment of a breast form constructed in accordance with this invention;

Fig. 2 is a diametrical sectional view on the line 2—2 of Fig. 1;

Fig. 3 is a diametrical sectional view of an outer pad constituting a part of the breast form and consisting, preferably, of felt;

Fig. 4 is a front view of a spring, and

Fig. 5 is a sectional view of the inner pad, preferably of felt.

It has been found in practice that many of the breast forms now on the market are so made that, if they should be pressed in at the nipple, they are apt to stay that way and in fact there is nothing in them to obviate this difficulty. As stated above, the principal objects of this invention are to overcome this objection.

The main part of the breast form shown is made up of two concave members 10 and 11, preferably of felt, one of them being adapted to be received within the other, as shown in Fig. 2.

In the manufacture of the device, a spiral concave spring 12 is placed between these two pads 10 and 11 and supported between them in its outer convolution 13 around the edge. The edges of the pads are merrowed all around at 14 so as to provide a comparatively rigid structure around the edge in which the outer convolution 13 of wire can be received and held in substantially fixed position. It is by this convolution 13 that the spring is supported and, being concave the same as the pads 10 and 11, it is depended upon

to hold the outer pad in its convex position on the outside and hold the nipple 15 in its proper position or to restore it to that condition at once, if the pad is pushed in. These pads are shown each as made of four pieces of felt, secured together by radial seams 16 and 17 respectively, by which device the pieces of originally flat felt can be manipulated into the convex condition required.

It will be seen that, with this construction, whenever the pad is in a position as shown in Fig. 2 and pressure is applied to the nipple, it can be bent backwardly against the resistance of the spring, but the spring will promptly return it to its normal convex condition. This avoids the difficulty often encountered, wherein the nipple of a breast form of this nature gets pressed in and remains in that condition. There is nothing behind it to restore it as the interior of the pad is not resilient and the desired effect cannot be accomplished, if that happens. The pad will stay collapsed until it is taken off and restored to shape.

Although it is preferred to use a wire spiral concave spring, a spring of the same general shape formed of featherbone will accomplish the same object. The shape of the coil spring prevents the retraction of the center of the bust inwardly by accident to such an extent as to rub on the natural nipple of the wearer or press on it in any way.

Having thus described my invention and the advantages thereof, I do not wish to be limited to the details herein disclosed, otherwise than as set forth in the claim, but what I claim is:

As an article of manufacture, a breast form comprising two convex cups of felt, concentric with each other, one within the other, their edges being merrowed in position, and a convex spiral metal spring between the two layers of felt for restoring the outer cup to its original convex position if it becomes indented in the center.

HERBERT A. AUSTIN.
